STEEL WOOL PAD

Herbert A. Dyer, Far Rockaway, N. Y., assignor
to American Steel Wool Mfg. Co. Inc., New
York, N. Y.

Application September 27, 1934, Serial No. 745,666

1 Claim. (Cl. 15—209)

This invention relates to abrasive pads and, more particularly to steel wool pads intended primarily for industrial purposes.

In the use of steel wool pads of prior known constructions, the abrasive action of the pad is very uneven because the pressure applied to the pad is not distributed uniformly over the surface which is in contact with the object subjected to its action. For this reason, the abrading action of the pad is irregular and, in some instances, alternate ridges and depressions are formed in the surface of the object due to the fact that the pad is so held and the pressure is so applied that a relatively high pressure is exerted in the region proximate the fingertips while a relatively low pressure is exerted at other portions of the pad.

An object of the present invention is to provide a steel wool pad so constructed that the pressure applied thereto in using the pad is distributed uniformly over the entire surface in contact with the work.

It has been proposed to form laminated steel wool pads so that successive layers of the pad could be removed when they lose their abrasive action whereby to expose unused portions of the pad. It has been proposed to form a pad of this type by spirally winding on itself a flat strip of steel wool, made up of steel wool strands extending longitudinally of the strip, and to subsequently expose unused portions of the pad by unwinding said strip. However, in pads of this type, it is difficult to properly remove the used outer layer from the adjacent unused layer because during the use of the pad the uneven pressure exerted thereon causes the layers to become so matted or entangled that in attempting to remove a used layer, portions of the adjacent unused layer are also removed and when the used layer tears, which is frequently the case, portions thereof remain attached to the adjacent unused layer. Thus, there usually results a waste of material due to the removal of unused steel wool, and an unsatisfactory abrasive surface is formed because of the presence of adhered portions of used steel wool of reduced or negligible abrasive or polishing properties.

Another object of the present invention is to provide a laminated steel wool pad in which the used layer can be removed readily from the adjacent unused layer.

A further object of this invention is to provide a pad of predetermined size and shape and so constructed that it can be operated by a machine.

A yet further object of this invention is generally to improve the construction of steel wool pads whereby to obtain improved results in the utilization thereof.

According to a preferred embodiment of this invention, there is disposed within the pad a substantially rigid flat core or plate located between a plurality of substantially flat layers of steel wool in a plane parallel with the upper and lower surfaces of the pad. Said plate is coextensive in length and substantially coextensive in width with the length and width, respectively, of the steel wool layers of the pad. By virtue of this construction, pressure exerted on the pad during its use is distributed evenly over the active surface of the pad so that a uniform abrading action is obtained, distortion of the pad is prevented, and the layers of steel wool are maintained in such condition as to permit a used layer to be unwound without being torn and without removing portions of the adjacent unused layer.

The invention will best be understood from the following description read in connection with the accompanying drawing.

In the drawing:

Fig. 1 is a perspective view of a steel wool pad embodying the present invention;

Fig. 2 is a perspective view of a strip or ribbon of arbitrary length of steel wool which may be employed in forming the pad shown in Fig. 1;

Fig. 3 is a section on the line 3—3 of Fig. 1;

Figs. 4 and 5 are views of cores of modified constructions which may be used in the pad shown in Fig. 1.

According to the present invention the steel wool pad 10 shown in Fig. 1 comprises a plurality of steel wool layers 12 and a pressure distributing member here shown as a flat rectangular core or plate 14 disposed between said layers and preferably coextensive in length therewith. The core or plate 14 is of substantial rigidity whereby the pressure applied to the pad during its use is distributed uniformly over substantially the entire area of the active or abrading surface of the pad in contact with the object subjected to the action of said surface. For this purpose, the plate 14 may be made of card board, wood or other suitable material, of a thickness which affords this function. It will be understood, however, that while the plate 14 is sufficiently rigid thus to distribute uniformly the pressure exerted on the pad, said plate is preferably sufficiently flexible to permit the use of the pad on objects having curved surfaces. If

desired, a handle or holder may be attached to the pad to facilitate its manipulation.

In the construction shown in Fig. 1, the side edges 16 of the core 14 are smooth and the core is of uniform width. As there is a substantial amount of friction between the edges 16 of the core and the adjacent layer of steel wool, the core is securely held in position within the pad. However, in order to more securely lock the core within the pad or to prevent the steel wool layers from being displaced longitudinally of the core, particularly when the steel wool layers are wound somewhat loosely, either of the core constructions shown in Figs. 4 and 5 may be utilized. For this purpose, in the construction shown in Fig. 4, the core 14a is provided with rough or serrated edges 16a. In the construction shown in Fig. 5, the core 14b is provided with lateral extensions 18 defining side edges 16c which are engaged by the steel wool strip when the latter is wound on the core, said extensions engaging opposite ends of the said layers, thereby to prevent the latter from being displaced longitudinally of the core. In other respects the cores 14a and 14b are of the same construction as the core 14.

As shown in Fig. 1, the layers 12 are formed by winding a steel wool strip 12', illustrated in Fig. 2, about the plate 14, initially in engagement with the side edges 16 of said plate and subsequently in engagement with the adjacent inner layer of steel wool, the engagement of said layers at the edges of the pad being along substantially circular arcs of about 180° and the engagement of said layers at the sides of the pad being substantially in flat planes spaced from each other by the thickness of each layer. The strip 12' of which the pad is formed is composed of a suitable thickness of steel wool strands which extend longitudinally of the strip in substantially parallel relation, said strands, however, being somewhat irregular and wavy and, therefore, interlocking with each other to form a compact strip. In forming said strip, loose steel wool strands are arranged in longitudinally extending and substantially parallel relation and are then compressed to form a compact strip which will provide the definite layers 12 of substantially uniform thickness in the pad 10 when wound about the plate 14.

The pad as thus constructed is well adapted to accomplish the objects of this invention, since

the substantially rigid plate prevents excess pressure from being exerted in some portions of the active surface of the pad while insufficient pressure is exerted on other portions of said surface. Thus, a uniform abrading or polishing action of great efficiency is obtained and the steel wool is maintained substantially in its original well defined layers so that a used layer can be readily unwound and reversed to permit use of its opposite unused surface or to permit its removal from the pad to expose for use an adjacent unused layer. Also, said plate prevents distortion of the pad and maintains the abrading surface thereof in flat uni-planor condition. Furthermore, the size and shape of the pad is predetermined and maintained constant by the plate, and as the size and shape of the pad is thus maintained constant substantially throughout its life, it can be used as a tool in an abrading or polishing machine.

While the preferred embodiment of the present pad and several modifications of the pressure distributing member have been disclosed, it will be understood that the constructions disclosed are not exhaustive of the practical embodiments of the present invention. Therefore, I do not wish to be limited to the precise constructions shown except as may be required by the appended claim.

What I claim is:

An abrasive pad for industrial use, said pad comprising a substantially rigid and relatively thin flat plate made of wood, cardboard, or the like, having rough serrated edges, and a flat ribbon of steel wool engaging the side edges and opposite sides of said plate, said engagement serving to prevent longitudinal displacement of the ribbon relative to the plate, said plate causing pressure applied to the pad in using the same to be distributed substantially uniformly over the entire surface area of the pad in contact with the object subjected to the action of said surface, said ribbon being wound spirally about said pad forming a plurality of flat layers of steel wool capable of being unwound after the pad has been used to expose the surface of an unused layer, substantially without disintegration thereof or substantial cohesion between portions of the unwound layer and the adjacent unused layer.
